UNITED STATES PATENT OFFICE

MARK HARRIS, OF NEW ROCHELLE, NEW YORK

DESIGN FOR A GAME TABLE

Application filed September 3, 1930. Serial No. 36,855. Term of patent 14 years.

To all whom it may concern:

Be it known that I, MARK HARRIS, a citizen of the United States, residing at New Rochelle, county of Westchester, and State of New York, have invented a new, original, and ornamental Design for a Game Table, of which the following is a specification, reference being had to the accompanying drawing, forming a part thereof.

Fig. 1 is a plan view of a game table showing my new design; and

Fig. 2 is a side perspective view showing the legs and also a lower panel of the table in broken lines.

I claim:

The ornamental design for a game table as shown.

MARK HARRIS.
